UNITED STATES PATENT OFFICE.

JAMES A. BREEN, OF WASHINGTON, DISTRICT OF COLUMBIA, ASSIGNOR OF ONE-HALF
TO HARRY H. MILLER, OF WASHINGTON, DISTRICT OF COLUMBIA.

MORSE TRANSMITTER.

1,276,617.

Specification of Letters Patent. Patented Aug. 20, 1918.

Application filed December 6, 1917. Serial No. 205,761.

To all whom it may concern:

Be it known that I, JAMES A. BREEN, a citizen of the United States, residing at Washington, in the District of Columbia, 5 have invented certain new and useful Improvements in Morse Transmitters, of which the following is a specification.

My invention has for its principal object the provision of a novel form of Morse 10 transmitter which will lessen the labor of telegraphing, and has special reference to a novel mechanism whereby a circuit-closer may be actuated to make and break the circuit to make a plurality of "dots" by a single 15 movement of the "dot" lever.

Another object is the provision of an exceedingly simple construction of Morse transmitter.

Other objects will appear as the specification 20 proceeds and the nature of the invention more fully appears.

In the accompanying drawings, forming part of this specification, in which like reference-characters denote corresponding parts 25 throughout the several views:

Figure 1 is a top plan view of my transmitter;

Fig. 2 is a view in side elevation thereof;

Fig. 3 is a transverse vertical sectional 30 view, on the line 3—3, Fig. 1, looking in the direction of the arrows;

Fig. 4 is a top plan view of a variation, in which a plurality of "dot" keys are provided, which are selectively used to make 35 a predetermined number of dots by a single movement of the particular key;

Fig. 5 is an end elevation of the mechanism shown in Fig. 4;

Fig. 6 is a transverse vertical sectional 40 view, on the line 6—6, Fig. 4; and

Fig. 7 is a detail view of the clutch-pawl used with both forms of my invention.

Referring, now, in detail to the drawings, and, first, to Figs. 1 to 3 thereof:

45 1 designates a base-plate of insulating material supporting the operative parts of my transmitter.

2 designates a manually-operable lever 50 loosely fulcrumed, at one end, on a pin 3, having a lower, cross-sectionally squared portion 4 seated in the base. The lever is, as shown, in two sections, one section, constituting the handle, 2^a, being connected, at one end thereof, to the other portion by a 55 pivot 5. The handle is provided, at its piv-

oted end, with a lip 2^b, the lever 2 being recessed correspondingly to receive the lip, as clearly shown in Fig. 1. Thus, the handle 2^a is capable of pivotal movement in one direction, but is held from such movement 60 in the other direction. A flat leaf-spring 2^c, secured at one end thereof to the lever 2, bears, at its free end, upon said lip 2^b, and serves to return the handle 2^a to normal position after pivotal movement thereof. 65 That portion of the handle 2^a which is grasped by the operator is of electrical non-conducting material, as indicated in the drawings; but the handle is provided with an insert 2^d of electrical conducting ma- 70 terial, and, in the normal position of the lever 2, this insert 2^d bears up on a contact-member 6 carried by the base 1, and having a conductor 7 leading therefrom to one of the line-wires 8. The lever 2 is, also, pro- 75 vided with an electrical non-conducting insert 9.

The handle 2^a may be provided with an electrical contact 10, which, when the handle is pivotally moved, strikes a stationary con- 80 tact 11 carried by the base 1, thus closing the electrical circuit through the conductor 12 leading from said contact 11 to the line-wire 13. A stop 14 carried by the base limits movement of the lever 2 in one direction and 85 holds it so that the contact 10 is spaced from the contact 11, whereby it is necessary for the operator to move the handle 2^a on its pivot 5 in order to close the electric circuit through the contacts 10 and 11. A second 90 stop 15 limits movement of the lever 2 in the opposite direction, and is so disposed on the base 1 that the full movement of the lever 2 from the stop 14 to the stop 15 will, through intermediate mechanism, cause the toothed 95 wheel 21 (more particularly to be described hereinafter) to revolve until the pawl 23 of the circuit-closer 22 rides over six teeth thereof, thus making and breaking the circuit six times, making six "dots"—a succession of six "dots" being the greatest number used in the Morse telegraphic code. A spring 16, secured at one end thereof to a pin 17 carried by the base 1 and, at its other end, to the lever 2, automatically returns 100 the latter to normal position against the stop 14, after manual movement thereof by the operator.

Seated in a recess in the lever 2, toward the fulcrumed end thereof, is a clutch-pawl 110

18, outwardly pressed by a coiled spring 19 in the bottom of said recess, said pawl engaging a small ratchet 20 concentric and integral with the toothed wheel 21 loosely mounted on the axial pin 3. The teeth of the wheel 21 are continuous throughout the circumference thereof.

Engaging with the teeth of said wheel 21 is the pawl-end 23 of the circuit-closer 22, 10 which may be of various constructions, but, in this instance, is exemplified as a rod pivoted intermediate its length, at 22', so as to oscillate or rock, when the pawl-end 23 rides over the teeth of the wheel 21, and bring the 15 free end thereof against an electrical contact 25 carried by a binding-post 25' from which leads a conductor 26 to a binding-post 27, to which the line-wire 8 is connected. A conductor 28 leads from the pivotal point 20 22' of the oscillating rod or circuit-closer 22 to a binding-post 29, to which the line-wire 13 is connected. An adjustable stop 24 carried by a post 24' may be provided to limit movement of the circuit-closer 22 in a 25 direction away from the contact 25; though this is not absolutely necessary, in view of the provision of a retractile coiled spring 30, secured, at one end thereof, to the rod 22 between the pivot 22' and the pawl-end 23, 30 and, at its other end to a pin 31, which spring operates to keep the pawl-end 23 of the circuit-closer 22 in constant engagement with the teeth of the wheel 21.

In operation, the lever 2, when the operator desires to make dots, is moved toward the right in Fig. 1, to make one dot, or any succession of dots up to six, as may be desired. By the construction described, such movement of the lever 2 will partially revolve the wheel 21, so that the circuit-closer 22 is oscillated to make and break the circuit. An operator soon becomes sufficiently proficient to tell, by "feel", just how far to move the lever 2 to make a predetermined 45 number of dots, less than six, and is able to move the lever with sufficient celerity. Of course, when it is desired to make a succession of six dots, all that has to be done is to move the lever 2 until it strikes the stop 50 15. To make dashes, the handle 2^a of the lever is moved on its pivot 5 so as to bring the contact 10 against the contact 11, thus closing the electric circuit.

It will thus be apparent from the description, taken in connection with the drawings, 55 that both the construction and operation of the transmitter are exceedingly simple; and that, by a single movement of the lever 2, any number of dots may be made, up to six, 60 as may be desired.

Referring, now, in detail, to the form of my invention shown in Figs. 4 to 6, inclusive, in this construction, a plurality of "dot" key-levers are used, six in number, being designated by the reference-numeral 32, each of

which is provided, at one end thereof, with a yoke 33 loosely mounted on a shaft 34 suitably supported in bearings in standards 35. Each of the key-levers 32 is provided with a spring-pressed pawl 36 meshing with the 70 teeth of a ratchet-wheel 37 fast on the shaft 34. The ratchet-wheels are of differing diameters, as shown, for a purpose presently appearing.

Fast on the shaft 34 is a toothed wheel 38 75 engaged by an oscillating bar 39 pivoted intermediate its length at 40 on a standard 41 carried by the base 1^a. One end of the bar or rod 39 is disposed in proximity to the electric contact 42. A retractile coiled spring 80 43 connected at one end to the bar 39 between the support 41 and the wheel 38 and, at its other end, to the base 1^a, serves to maintain the pawl end 39^a of the circuit-closer 39 in engagement with the teeth of the wheel 38. 85

Each of the key-levers is manually depressed against the influence of a coiled spring 44 interposed between the key 45 and the base 1^a, which spring returns the key levers to normal position after depression 90 thereof.

A bar 46 disposed transversely across all of the key-levers 32 limits upward movement of the key-levers.

The key-lever 32 controlling movement of 95 the ratchet-wheel 37 having the largest diameter will rotate or move the toothed wheel 38, so that the pawl-end 39^a will ride over one tooth thereof, thus causing the circuit-closer 39 to make and break the circuit once, 100 making one "dot," according to the Morse code. Movement of the next adjacent key-lever 32 will cause the circuit closer 39 to make and break the circuit twice, to make two "dots"; and so on. 105

47 designates a dash key, which may be of the conventional type.

Having thus fully described my invention, what I claim as new and desire to secure by Letters Patent is:

1. In a Morse transmitter, the combination, with a normally open electric circuit, of a movable circuit-closing member, a revoluble toothed wheel engaging said circuit-closing member, a ratchet carried by said wheel, a lever carrying a pawl engaging with said ratchet for rotating said wheel, an operating-handle pivoted to said lever, a contact-plate upon which said handle bears, and an electric contact with which said handle contacts upon pivotal movement thereof. 115

2. In a Morse transmitter, the combination, with a normally open electric circuit, of a movable circuit-closing member, a revoluble toothed wheel engaging said circuit-closing member, a ratchet carried by said wheel, a lever carrying a pawl engaging with said ratchet for rotating said wheel, an operating-handle pivoted to said 120 handle, and a dash key. 125

lever, means carried by said handle for preventing pivotal movement thereof in one direction, a contact-plate upon which said handle bears, and an electric contact 5 with which said handle contacts upon pivotal movement thereof.

3. In a Morse transmitter, the combination, with a normally open electric circuit, of a movable circuit-closing member, a rev-
10 oluble toothed wheel engaging said circuit-closing member, a ratchet carried by said wheel, a lever carrying a pawl engag-
ing with said ratchet for rotating said wheel, an operating-handle pivoted to said lever, means carried by said lever for re-
turning said handle to normal position af-

ter pivotal movement thereof, a contact-plate upon which said handle bears, and an electric contact with which said handle contacts upon pivotal movement thereof. 20

4. In a Morse transmitter, the combina-
tion, with a normally-open electric circuit,
of a movable circuit-closing member, lever-
controlled mechanism for moving said cir-
cuit-closing member to make and break the 25
circuit, and a handle pivoted to said lever
and operable by pivotal movement to make
and break said circuit independently of
said circuit-closing member.

In testimony whereof, I affix my signa- 30
ture.

JAMES A. BREEN.
